(57) **CLAIM**

The ornamental design for a protective cage and radio combination, as shown and described.

DESCRIPTION

FIG. 1 is a front perspective view of a protective cage and radio combination showing our new design;

FIG. 2 is an enlarged front elevational view thereof;
FIG. 3 is a right side view thereof, the left side being a mirror image thereof;

FIG. 4 is a rear elevational view thereof;

FIG. 5 is a top plan view thereof; and,

FIG. 6 is a bottom plan view thereof.

The broken line showing of connectors for attaching the radio to the protective cage and other details is for illustrative purposes only and forms no part of the claimed design.

1 Claim, 5 Drawing Sheets
